RACK FOR DISPLAYING BANANAS

Frank R. King and Geneva King, both of 2140 Mann
Drive, Beech Grove, Ind. 46107

Filed Sept. 26, 1973, Ser. No. 401,027

Term of patent 14 years

Int. Cl. D6—04

U.S. Cl. D6—113

FIG. 1 is a front perspective view of a rack for displaying bananas embodying our new design;

FIG. 2 is a side elevational view taken from the right of FIG. 1; and

FIG. 3 is a side elevational view taken from the left of FIG. 1.

The method of suspending the rack for displaying bananas is shown in broken lines in FIGS. 1, 2 and 3.

We claim:

The ornamental design for a rack for displaying bananas, substantially as shown and described.
